UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

FEEDER FOR INGOT MOLDS.

Application filed February 15, 1924. Serial No. 693,093.

To all whom it may concern:

Be it known that BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Feeders for Ingot Molds, of which the following 10 is a specification.

Our invention relates to improvements in feeders for ingot molds.

The object of our invention is to provide 15 a feeder for ingot molds adapted to be supported on the upper end of the mold and also provide a feeder which will prevent the formation of what is known as "piping" and at the same time reduce segregation.

Another object of our invention is to provide 20 a feeder having a number of walls adapted to correspond with the walls of the mold and which has a marked advantage in that it more nearly conforms to the shape of the article to be rolled from the ingot and 25 to enable the imperfections in the outer surface of the ingot to be more readily rolled out and also cause the scale on the surface of the ingot to more readily peel off during the rolling process.

30 A further object of our invention is to provide a feeder of this character having certain arrangement of walls to accomplish the above result and at the same time provide a simple cheap and effective feeder.

35 In the accompanying drawings:

Figure 1 is a perspective view of an ingot mold showing a feeder thereon embodying our invention.

40 Figure 2 is a vertical transverse sectional view of Figure 1.

Figure 3 is a top plan view showing a modified form of feeder in which the walls are bellied inwardly.

45 Figure 4 is a top plan view of the form shown in Figure 3 with straight wall faces.

Figure 5 is a top plan view of Figure 3 showing a straight circular interior wall.

Figure 6 is a top plan view of Figure 1 showing a straight circular interior wall.

50 Figure 7 is a top plan view of Figure 1

showing the inner walls bellied inwardly and the outer walls straight.

Referring now to the drawings 1 represents the mold, and 2 the feeder. The feeder as shown is octagonal in cross section having 55 the eight walls and the outer face of a number of walls provided with vertically disposed ribs 3 semi-circular in cross section. While we have shown these ribs 3 arranged on four of the walls it will be understood 60 that each wall could be provided with a rib or any desired number of ribs can be employed.

In Figure 3 of the drawings, we have 65 shown an octagon shaped feeder in which the eight walls are bellied inwardly as indicated at 4 and are connected by outwardly bellied walls 5, the arc of a circle of the walls 5 being considerably less than that of the walls 4. If this form like that shown 70 in Figures 1 and 2 any number of the walls may be provided on their outer faces with vertically disposed ribs 6 semi-circular in cross section.

In Figure 4 we have shown the eight walls 75 curved inwardly and their inner faces straight as indicated at 7.

In Figure 5 the inner wall is shown circular in contour as indicated at 8.

Figure 6 is a top plan view similar to 80 Figure 1 showing the inner wall also of circular contour as indicated at 9.

Figure 7 shows the form shown in Figure 1 with inwardly bellied walls as indicated at 10.

Having thus fully described our invention what we claim is:

1. A feeder for ingot molds comprising 85 eight walls bellied inwardly and connected by outwardly bellied walls.

2. A feeder for ingot molds comprising a body portion composed of eight inwardly bellied walls connected by outwardly bellied walls the arc of which is less than the inwardly bellied walls.

3. A feeder for ingot molds comprising a body portion formed of eight curved walls connected by curved walls, the arc of which is less than that of the first mentioned walls.

4. A feeder for ingot molds comprising a 100

body portion formed of eight curved walls connected by eight short curved walls, the arc of which is less than that of the first mentioned walls.

5. A feeder for ingot molds comprising a body portion having eight curved walls connected by eight short curved walls ex-

tending the opposite direction and arranged in a different arc of the circle from that of the first mentioned walls.

In testimony whereof we affix our signatures.

BLOOMFIELD H. HOWARD.
ERNEST J. TURNER.
